UNITED STATES PATENT OFFICE.

HOWARD M. NICHOLSON, OF PITTSBURGH, PENNSYLVANIA.

CHECK VALVE.

Application filed June 19, 1925. Serial No. 38,183.

My invention relates to check valves, that is, to valves of the type adapted to permit the flow of fluid through the valve in one direction but to oppose the flow of such fluid through the valve in the opposite direction.

Check valves embodying my invention are particularly adapted for, though in no way limited to, use as foot valves in connection with pumps, such as used for dispensing gasoline.

I will describe one form of check valve embodying my invention and will then point out the novel features thereof in claim.

15 In the accompanying drawing, Fig. 1 is a vertical sectional view showing one form of check valve embodying my invention with the valve closed. Fig. 2 is a view showing the valve illustrated in Fig. 1 with the valve open. Fig. 3 is a sectional view along the line III—III of Fig. 2. Fig. 4 is a view, partly diagrammatic, showing one form of gasoline dispensing apparatus in which is incorporated the valve shown in the preceding views.

Similar reference characters refer to similar parts in each of the several views.

Referring first to Fig. 1, the valve, designated in general by the reference character 30 V, comprises a casing A of suitable shape and material. As here shown this casing is cylindrical. The top plate A' of this casing is provided with an outlet opening, here shown as a pipe 1. Extending upwardly in the casing A is a frusto conical valve seat 2 having its faces sloping inwardly toward an inlet opening 3 in the top of the seat. The lower edge of the seat 2 is attached to the casing A at its bottom, as will be plain 35 from the drawing. A mass of mercury 7 is introduced into the casing A and occupies the annular space around the lower edge of the seat 2.

40 Resting freely on seat 2 is a frusto conical valve cap 4. The parts are so proportioned that when the flat top 4^a of cap 4 rests on the top of the valve seat 2, the side walls of the valve cap are spaced from the slant faces of the valve seat by a very small 45 annular clearance space or passage 5. Under this condition the lower edge 6 of the valve cap is immersed in the mercury 7. If now a fluid is admitted to the valve through pipe 1, which fluid tends to flow through the

55 valve to opening 3 in valve seat 2, the pressure exerted on this fluid is transmitted to the mercury 7 and forces the mercury into the passage 5 between the cap 4 and the seat 2. The mercury in this passage then rises to a level 7^a sufficient to create a static 60 head which is equal to the pressure tending to force the fluid through the valve. Because of the high specific gravity of mercury, a head of a few inches of mercury in the passage 5 of the valve is sufficient to prevent the flow of some light fluid, such as 65 gasoline, under a pressure of many feet of such fluid.

Referring now to Figs. 2 and 3, when 70 fluid is forced into the valve through the inlet opening 3 by pressure which tends to cause a flow of such fluid to outlet pipe 1, this pressure lifts cap 4 upwardly out of engagement with the valve seat. Motion of the cap upwardly is limited by a strap metal 75 guard 8 attached to the under side of top plate A'. The parts are so proportioned that when the cap is in its extreme upper position, the cross-sectional area of the annular space between the seat and the cap is 80 equal to the area of the space between the lower edge 6 of the cap and the walls of the casing. When the cap is in this position, the maximum discharge through the valve is possible, the mercury 7, of course, 85 falling into the pocket between the lower edge 7 of the seat 2 and the casing A. The level of the mercury is then well below the lower edge of the cap 4. An unrestricted path is thereby provided for the fluid to 90 flow upwardly through the valve from inlet opening 3, downwardly between the cap 4 and the seat 2, and upwardly between the cap 4 and the casing A, to pipe 1.

Should the flow of the fluid be reversed, 95 the cap 4 would immediately return to the position in which it is illustrated in Fig. 1, and the mercury 7 would be forced into the restricted clearance space between the cap and the valve seat to oppose flow of the fluid 100 in the reverse direction.

One advantage of a check valve embodying my invention is that when the valve is open to permit the flow of fluid therethrough, a substantially unrestricted path 105 is provided for such fluid, but that when the fluid tends to flow through the valve in the opposite direction the passage 5 between the

cap 4 and the seat 2 is diminished and a comparatively small volume of mercury is therefore sufficient to maintain a substantial static head to oppose flow of fluid through the valve in the latter direction.

In Fig. 4 the reference character P designates a simple form of pump, such as is used for dispensing gasoline. The gasoline is contained in a storage tank T, usually buried 10 below the surface of the ground G. The casing A of a valve V similar to that shown in Figs. 1, 2 and 3, is placed in the tank T, immersed in the gasoline therein, and the outlet pipe 1 is connected with the cylinder 17 of the pump P. This cylinder contains a piston 11 attached to a rod 12 operated by a crank 10 through suitable gearing. The piston 11 is provided with a port 14 and a flap valve co-operating therewith. 15

When handle 10 of the pump P is operated to move the piston upwardly, gasoline is drawn from the tank, through the valve V and pipe 1 into cylinder 17. When the crank 10 is next operated to move the piston 11 downwardly, the check valve V prevents the return of fluid to the tank, and flap valve 13 on piston 11 lifts so that the gasoline flows through port 14 to the cylinder 17 above the piston. On the next upward stroke of the piston 11, valve 13 closes, and while gasoline is drawn from the tank into the cylinder below the piston, the gasoline above the piston is discharged through pipe 15 to the dispensing nozzle 16. The cylinder 17 and the stroke of the piston 11 are so proportioned that each operation of the pump discharges a measured quantity of gasoline to the nozzle 16. Obviously, with such an arrangement, it is desirable that the

gasoline be prevented from flowing back 40 into the tank when the pump is idle.

A check valve embodying my invention 45 accomplishes this desirable result perfectly, because with such a valve it is impossible for any gasoline to return to the tank.

I have herein illustrated the check valve V as a foot valve for a gasoline dispensing pump, but I wish it to be understood that my invention is not limited to such use, but that check valves embodying my invention 50 may be used wherever it is desired to permit the flow of a fluid through a valve in one direction but to prevent such flow in the opposite direction.

Although I have herein shown and described only one form of check valve embodying my invention, it is understood that various changes and modifications may be made therein within the scope of the appended claim without departing from the 55 spirit and scope of my invention.

Having thus described my invention, what I claim is:

A valve comprising a casing provided at its top with an outlet opening, an upstanding conical seat in the casing having an inlet opening in its top, a mass of mercury in the casing surrounding the base of the seat, and a frusto-conical cap having a flat top adapted at times to engage the top of 65 the seat and having side walls parallel throughout the length of the cap to the walls of the seat but spaced from the seat by an annular air gap, the lower edge of the cap being immersed in the mercury when 70 the cap rests upon the seat.

In testimony whereof I affix my signature.
HOWARD M. NICHOLSON.
